UNITED STATES PATENT OFFICE.

WINTER W. MYERS, OF BROOKLYN, NEW YORK, ASSIGNEE TO AUSTRAL WINDOW COMPANY, OF NEW YORK, N. Y., A CORPORATION OF MAINE.

FASTENING MEANS FOR WINDOWS.

1,326,956.

Specification of Letters Patent.

Patented Jan. 6, 1920.

Application filed July 21, 1917. Serial No. 181,944.

To all whom it may concern:

Be it known that I, WINTER W. MYERS, a citizen of the United States, residing at Brooklyn, in the county of Kings and State 5 of New York, have invented certain new and useful Improvements in Fastening Means for Windows, of which the following is a full, clear, and exact description.

The invention which constitutes the subject matter of this application relates to a fastening means for window sashes. The device is particularly applicable to balanced windows of the "Austral" type.

In the drawings:

15 Figure 1 is a vertical cross-sectional view of the ordinary "Austral" window showing my invention applied thereto.

20 Fig. 2 is an enlarged view of the meeting rails of the two sashes showing my improvement also in cross section.

Fig. 3 is an end view of the fastening means.

Fig. 4 is a cross section thereof on the line 4—4 of Fig. 2.

25 Fig. 5 is a cross-sectional view of the ordinary "Austral" window illustrating a slightly modified form of my invention.

Fig. 6 is an enlarged view thereof with parts broken away to show detailed constructions of Fig. 5.

Fig. 7 is a top plan view and

Fig. 8 is an end view of the modified form shown in Fig. 5.

Fig. 9 is a perspective view of the construction shown in Figs. 1 to 4, inclusive.

Referring to Figs. 1 to 4 in detail, the reference numeral 10 designates a frame in which the two sashes 11 and 12 are mounted, the former being provided with sliding 40 pivots at the top and the latter with sliding pivots at the bottom. These two sashes are pivotally connected to balance arms 13 (one being shown) so that when one of said sashes is moved the other is simultaneously moved 45 with it. The details of construction and operation will be clear from the prior re-issue patent of E. G. Abell, No. 12,048, and the patent to A. Knox 821,510, to which reference is hereby made.

50 Located upon the meeting rail 14 of the lower sash is secured the base member 15 of the fastening means. This member 15 is provided with a horizontal perforation 16 through which the securing bolt 17 is adapt-

ed to project, the outer end of which is provided with a pivoted camming or tightening member 18 and the inner end of which is provided with a hook adapted to be cammed upwardly by, and to engage over, the keeper plate 19. The bolt 17 is provided with a shoulder 20, and interposed between this shoulder and the base member 15 is a spiral spring 21 which serves to maintain the bolt at its extreme inward position whenever the camming member 18 is in the dotted line 65 position shown in Fig. 2.

The base member 15 is provided with a counter-bore 22 so as to permit a movement of the inner end of bolt 17 in a vertical plane. Fig. 2 shows the improved fastening means 70 in normal position with the sashes closed. When it is desired to open the sashes any suitable instrument is made to engage with the camming member 18 and the latter pulled downwardly to the dotted line position when the said member will engage with the extension 23 of the bolt 17. Simultaneously with this movement the bolt 17, under the power of the spring 21, will be moved inwardly to the dotted line position shown. 80 If the movement of the camming member 18 is continued this movement will be imparted to the extension 23 and cause the inner end of bolt 17 to move sufficiently in a vertical direction to permit the said bolt 85 and said keeper plate 19 to be out of each other's path of movement as the sashes are being opened.

From the above description it will be seen that when the sashes are moved to closed 90 position the member 18 will be in the dotted line position, illustrated in Fig. 2, and the engagement of the bolt 17 with the keeper plate 19 will be effected automatically. After this engagement the sashes cannot be 95 opened from the exterior; in other words, they are locked in closed position. If it is desired to open the sashes a downward pull from its dotted line position shown in Fig. 2 of the member 18 will be necessary. This 100 downward pull of the member 18 is imparted to the extension 23 and results in an upward movement of the inner end of the bolt 17. On the other hand, if it is desired to effect an air-tight engagement between the meeting 105 rails of the sashes the member 18 is moved to full line position shown in Fig. 2, and, owing to the eccentric movement of the ears

24 about their pivotal points, the base member 15 and keeper plate 19 will be drawn toward each other, thus effecting a corresponding movement toward each other of 5 the meeting rails of the sashes.

It is clear from the above description and the accompanying illustrations that the improved latching device is particularly desirable where the meeting rails are out of 10 reach of the operator, as the same are as readily operable by means of a suitable pole as they are when manipulated directly by the hand of the operator.

In Figs. 5, 6, 7 and 8 is shown a modified 15 form of the invention and designed to be used, for instance, where the windows are out of reach of a hook. In this case the windows are opened by means of a cord 28 attached to a member or arm 25 which is 20 secured to the hook 17 by means of a suitable pin 26 which not only passes through said members 17 and 25 but also through perforations 27 in the housing 15. When thus assembled the hook member 17 has only 25 a pivotal movement about the pin 26 as a center but it will be clear from the above description that the only changes necessary in the substitution of the arm 18 for the arm 25 is the provision of perforations 27 in the body 15 and a pin sufficiently long to have bearings in the perforations 27 in the hook member 17. The opening of the windows is 30 accomplished by exerting a pull upon the cord 28. When it is desired to close the windows it is only necessary to exert a pull 35 upon the cord 29 which is connected to the outer sash, as will be understood. The spring 21 serves, as it does in Figs. 1 to 4 inclusive, to maintain the bolt member 17 in 40 a substantially horizontal position, that is to say, in substantially the position as indicated, for example, by the full lines in Fig. 6, thus enabling the said bolt member to automatically engage the keeper plate when 45 the sashes are moved from open to closed position.

What I claim is:

1. An improved window latch, comprising 50 a keeper plate adapted to be secured on the meeting rail of one sash, and a bolt member adapted to be supported on the meeting rail of the other sash and normally engaging said keeper plate, in combination with means including means pivoted to the bolt member adapted to move the latter first longitudinally and then vertically with respect to the meeting rails to unlatch the same.

2. An improved window latch, comprising, 60 in combination, a keeper plate adapted to be secured on the meeting rail of one sash, and a spring pressed bolt member adapted to be supported on the meeting rail of the other sash, and normally engaging said keeper plate, in combination with means 65 including means pivoted to the bolt member

adapted to move the latter first longitudinally and then vertically with respect to the meeting rails to unlatch the same.

3. An improved window latch comprising a keeper plate located on the meeting rail 70 of one sash, a base member fixed to the meeting rail of the other sash, and a plunger or bolt carried by said base member normally in locking engagement with said keeper plate, an operating lever pivoted to the bolt 75 for oscillating the latter and provided with a cam surface thereon coöperating with said base member for moving the same longitudinally in one direction, and means coöperating with said base member for moving said 80 bolt longitudinally in the other direction.

4. An improved window latch comprising a keeper plate located on the meeting rail of one sash, a base member fixed to the meeting rail of the other sash provided with a 85 pivot bearing and a spring pressed plunger or bolt carried by said base member and adapted to engage said keeper plate, said bolt and base member provided with means for attaching a pivoted or fixed operating 90 member for actuating the same.

5. An improved window latch comprising a keeper plate located on the meeting rail of one sash, a base member fixed to the meeting rail of the other sash, and a spring 95 pressed plunger or bolt operatively connected to said base member, adapted to automatically engage said keeper plate and capable of longitudinal and vertical movement with respect to the base member and means 100 pivoted to said bolt and adapted, when moved in one direction to make a tight joint between the said meeting rails and when moved in the other direction to move the same from the keeper plate.

6. An improved window latch, comprising a keeper plate on the meeting rail of one sash, a base member fixed to the meeting rail of the other sash adapted to receive a plunger or bolt therein, a plunger or bolt member, a spring engaging the said base member and plunger, and means pivotally secured to the said plunger or bolt adapted, when moved in one direction, to lock the said keeper plate and said plunger and when moved in the other direction to enable the spring to move the same from the keeper plate.

7. An improved window latch, comprising a keeper plate located on the meeting rail of one sash, a base member fixed to the meeting rail of the other sash, a bolt member adapted to be received in the said base member, a shoulder on the said bolt member, a spring adapted to engage the shoulder member and the base member, and a member pivotally secured to the bolt adapted when moved in one direction to enable the spring to move the bolt from the keeper plate and when moved in the other direction to effect 130

a tight joint at the meeting rails in locked position.

8. An improved window latch comprising a keeper plate adapted to be secured on the meeting rail of one sash, a base plate secured to the other sash, a bolt member supported by the base plate and normally engaging said keeper plate, means pivoted to said bolt member and coöperating with said base plate for moving the same in one direction longitudinally and also for imparting a movement of oscillation thereto, and means coöperating with the base plate for imparting a longitudinal movement in the other direction to said bolt member.

9. An improved window latch, comprising a keeper plate secured to the meeting rail of one sash, a movable bolt member supported on the meeting rail of the other sash and automatically locking the sashes when the said sashes are moved to closed position, and means pivoted to the bolt member adapted to move said bolt member longitudinally to effect a tight engagement between the meeting rails of the sashes.

10. An improved window latch, comprising a keeper plate secured to the meeting rail of one sash and a movable bolt member secured to the meeting rail of the other sash,

said keeper plate and bolt member provided with cooperating camming surfaces whereby they automatically lock the sashes when said sashes are moved to closed position, in combination with a camming member pivotally secured to and adapted to move said bolt member longitudinally to effect a tight engagement between the meeting rails of the sashes.

11. An improved window latch, comprising a keeper plate secured to the meeting rail of one sash, a movable bolt member secured to the meeting rail of the other sash, and a resilient means for maintaining said bolt member in proper relation to the keeper plate, said bolt member and keeper plate provided with camming surfaces whereby they automatically lock the sashes when the latter are moved to closed position, in combination with a camming member pivotally secured to and adapted to move said bolt member longitudinally against the tension of said resilient means to effect a tight engagement between the meeting rails of the sashes.

In testimony whereof I hereunto affix my signature.

WINTER W. MYERS.
